(57) CLAIM

The ornamental design of a glow in the dark egg, as shown and described.

DESCRIPTION

FIG. 1 is a perspective view of a glow in the dark egg showing the new design;

FIG. 2 is side elevational view of the FIG. 1 glow in the dark egg;

FIG. 3 is a plan view of the interior of the upper half of the FIG. 2 glow in the dark egg;

FIG. 4 is a top view of the FIG. 1 glow in the dark egg, showing the cross-sectional line 7—7;

FIG. 5 is a side elevational view (inverted) of the upper half of the FIG. 2 glow in the dark egg;

FIG. 6 is a perspective view of the top half of the FIG. 1 glow in the dark egg;

FIG. 7 is the cross-sectional view of the FIG. 1 glow in the dark egg, showing a glow-stick mounted between the upper and lower halves of the egg;

FIG. 8 is a plan view of the interior of the bottom half of the FIG. 1 glow in the dark egg;

FIG. 9 is a side elevational view of the lower half of the FIG. 2 glow in the dark egg;

FIG. 10 is a perspective view of the lower half of the FIG. 2 glow in the dark egg;

FIG. 11 is an end view of the light-stick shown in FIG. 7;

FIG. 12 is a right side elevational view of the light-stick shown in FIG. 7, the left side view being identical thereto;

FIG. 13 is a plan view of the light-stick shown in FIG. 7; and,

FIG. 14 is a perspective view illustrating the interaction of the three parts of claimed glow in the dark egg.
